CLAIM

The ornamental design for a television receiver, substantially as shown and described.

DESCRIPTION

FIG. 1 is a front, top and partial left side perspective view of a television receiver showing our new design; FIG. 2 is a left side elevational view, the right side being a mirror image thereof;

FIG. 3 is a top plan view; and

FIG. 4 is a rear elevational view.

The right side is identical to the left elevational view of FIG. 2.

Fig.1.

Fig.2.

Fig. 3.

Fig. 4.
